UNITED STATES PATENT OFFICE

ALFRED B. CHAPOLLA, ATTORNEY IN PATENTS

261.

1,198,324.

Specification of Patent No. 1,198,324, filed Sept. 10, 1916.

Application filed September 11, 1913. Serial No. 501,778.

To all whom it may concern:

Be it known that I, ALFRED B. CHAPOLLA, a citizen of the United States, and resident of Chicago, in the county of Cook and State of Illinois, have invented certain new and useful improvements in Caps, of which the following is a full, clear, and exact specification.

This invention relates to improvements in caps for men and boys, and also women, and may be in use, in which heretofore the fabric of the structure is protected by a sweat band of leather or other suitable non-elastic material, extending entirely around the head, back of the cap, of the crown and holding the cap in its adjusted operative position on the head of the wearer.

The aforesaid use of sweat bands of the character above, as is well known, requires caps to be made in several sizes, and as many as there are differing sizes of heads to be fitted, an objection heretofore sought to be remedied by entirely omitting the use of a continuous sweat band or a substantial portion thereof, and substituting therefor a viscose cord or tape, fixed at its free ends, and over which the band of the cap is gathered in folds, adjustable in size by the stretching of the cord or tape to fit the cap on the head of the wearer.

While elastic cords or tapes are no doubt the best means for adjusting the cap on the head, it is also well for holding a cap in its place, insuring against so-called "dead-heads" or "dead-aways" when the aforesaid cords or tapes are stretchable, because constantly stretching and obstructing the blood circulation of the scalp when at a tension sufficient to maintain the cap in its operative position, and for the further reason that the rubber of which they are composed has so little protection against oxidation produced by the resistance and the natural oil of the hair that such cords and tapes are very liable to break, lose their elasticity, and consequently new cords and tapes must be used, and therefore at no operation, above, is there any improvement.

The principal object of my invention, therefore, is to provide a cap with a sweat band continuous, as regards to the band of the wearer, and with a sweat band which is ad-

justable to a wide varying size of heads, and also, that other than the number of sizes of the cap, as applied may be substantially correspondingly increased.

Another and important object of my invention is a cap provided with a continuous sweat band of pieces of rubber cord, tape or the like, adjustable means concealed by the band of the cap, between which and the head of the wearer is interposed a yielding sweat band.

More especially, and the object of my invention is a cap provided with a continuous adjustable sweat band of non-elastic material, made adjustable to differing sizes of heads by sufficient means interposed between the sweat band and the surrounding fabric of the cap.

A further object of my invention is a cap provided with a sweat band which is continuous with reference to the head of the wearer, and especially adjustable to substantially different sizes of heads by means of an adjustable tape or other resilient means of the desired possible length located externally of the sweat band, and whereby the expense of more resilient materials is decreased, by reduced, and their normal 70 resistance considerably prolonged.

With these objects in view, my invention finds embodiment in certain features of construction, the combination and arrangement of parts, by which the said objects are secured, the details are attained, all of which are fully described with reference to the drawings, and more particularly indicated in the claims.

In said drawings Figure 1 illustrates in perspective a cap in which my invention finds embodiment in its operative position upon the head of a wearer. Fig. 2 is an enlarged side elevation of the adjustable sweat band with parts of the fabric of the cap broken away. Fig. 3 is a bottom plan view of the cap, showing the folding the folds in the cap, the sweat band and the sweat band being thereby partially concealed. Fig. 4 is a transverse section, on the line 4-4 of Fig. 1, taken in the direction of the arrows, and Fig. 5 is a longitudinal section of a transverse section of the cap taken on the line 5-5 of Fig. 1.

Similar characters of reference indicate the same parts in the several figures of the drawing.

- 6 indicates the crown or body of a cap
 5 composed of any suitable, foldable, woven or other fabric, and which may be of any desired form and style, and provided with the usual brim or vizor 7, and may be with an ornamental front band or strip 8.
 10 Secured to the inner face of the edge of the crown, as hereinafter described, is a sectional sweat band consisting of a rear member 9 and a front member 10, both of which members preferably consist of leather, or
 15 may be of any other non-resilient material commonly used for sweat bands, the length of which when taken together is greater than the circumference of the edge of the crown when fully distended, to the largest size of
 20 head it is adapted for.

The rear member 9 of the sweat band is secured as usual to the crown, preferably by means of stitches along its opposing edges as indicated at 11-11, thereby leaving its
 25 ends free and detached from the fabric of the cap.

The front member of the sweat band is as usual stitched only along its outer edge to the fabric of the cap, which stitching, however, for the purpose of my invention terminates at each side of the brim or vizor 7, or at such other point as to leave the opposite ends of the front member free, and whereby they form tongues 12-12 at each side of
 35 the cap, respectively projecting into pockets in the rear member of the sweat band before described, which tongues are preferably stiffened as indicated at 13 by means of featherbone, and may be by celluloid, paste
 40 board, or other suitable stiffening secured to the inner face of the sweat band, which preferably tapers toward a point as indicated in Fig. 2, for convenience of the insertion of the tongue to its operative position in the rear member of the sweat band.
 45 The free ends of both of these tongues 12-12 are freely movable in both an inward and outward direction of their respective pockets, their length however, being such
 50 that when the fabric of the cap is distended for the largest size of head for which it is adapted, the tongues will not be accidentally detached from their pockets.

Having shown and described a sweat band
 55 made in sections, one of which sections is provided at its ends with tongues telescoping in the other section at each side of the cap, it should now be observed that my invention is not to be limited thereto, but
 60 includes a sweat band formed from one piece, or strip, the ends of which telescope or otherwise have a sliding movement one upon the other, whereby it may be adjusted
 65 to heads substantially varying in size and contour. It is desirable, however, that sweat

bands so made shall be automatically adjustable by some means not objectionable to the wearer, and which will not destroy the symmetry or otherwise disfigure the cap, and which will retain its adjusting tension for a substantially indefinite time. To these ends there is secured at its ends at the opposite sides of the cap, a device 14 which may be a curved strip of thin steel, a coiled wire spring, etc., but which preferably is a rubber tape or cord externally of the sweat band, and confined between the fabric 6 of the cap and a textile strip or tape 15, which tape like the resilient means 14 being secured at one end as indicated at 16-16 to the fabric of the cap adjacent the socket end of the sweat band, and likewise at its opposite end adjacent the base of the tongue of the sweat band as indicated at 17, may serve to, and preferably limits the stretchability of the resilient means 14 whether it be a rubber cord or tape, or a metal spring, and thereby preventing them from being stretched to a degree reducing their normal elasticity and therefore tension.

When the resilient means is contracted small fulls or folds are thereby produced in the fabric of the cap, and also in the strip or tape 15, which straighten out more or less when the resilient means is stretched in fitting the cap to heads differing in size, the stretchability of the resilient means being such that for fitting the cap to a head of the smallest size for which it is intended that but little stretching is necessary therefor, followed with but a small degree of unfolding of the fulls in the fabric of the cap, which, however, are substantially straightened out when the cap is fitted to a head of the largest size for which it is intended, and in no instance are the fulls unsightly, but on the contrary, give a more or less ornamental effect and new design to the cap, interposed as they are between the ornamental strap 8 and may be between an upward outward fold 18 of a flap or strip of the material of which the crown of the cap is composed, and which is preferably of the same shade of material, though may be of some other shade. My invention, however, is not limited to these several details of construction, but includes first, a sweat band for a cap, which is adjustable by means of a telescoping or sliding connection, between its ends, and second, the employment of any resilient means concealed within the structure of the cap and isolated from the head of the wearer by any part of a substantially non-elastic sweat band adjacent thereto when operating to automatically adjust a sweat band to differing sizes of heads.

In conclusion it should be observed that my invention provides by the use of a very short length or lengths of a resilient means,

whether it be of resilient cord, tape or metal, and thereby providing for the greatest possible economy in this respect for adjusting a single cap to so many differing sizes of heads, that it is found in practice that but two differing sizes of crowns need be made for furnishing all of the several sizes now required to fit boys' and men's heads. It may also be finally observed that 5 my invention is adapted for desirability of use in connection with what are commonly known as soft or felt hats.

Having described my invention, what I claim and desire to secure by Letters Patent is:

1. A cap comprising in combination a continuous sweat band, means for adjusting said sweat band to differing sizes of heads, resilient means within and concealed 10 by the fabric of the cap for automatically contracting said sweat band located externally thereof, and whereby a cap is yieldingly adjustable to differing sizes of heads.
2. A cap comprising in combination a sweat band provided with telescoping ends,

and a concealed resilient means automatically resisting their movement from each other.

3. A cap comprising in combination a sweat band, one end of which is provided 30 with a pocket adapted to confine the opposing end thereof, and a resilient means externally of said band, and yieldingly projecting said end into the pocket.

4. A cap comprising in combination a 35 continuous sweat band one end of which is provided with a pocket adapted to movably confine the opposing end thereof, and a resilient means confined between said band and the fabric of the cap yieldingly moving 40 the opposing ends of the band toward each other.

In witness whereof, I have hereunto set my hand and affixed my seal, this 31st day of August, A. D. 1914.

ALFRED B. CHANDLER. [L. s.]
